UNITED STATES PATENT OFFICE.

FREDERICK BEND, OF BROOKLYN, ASSIGNOR TO BUCHANAN & LYALL, OF NEW YORK, N. Y.

DESIGN FOR A CARPET.

SPECIFICATION forming part of Design No. 14,135, dated July 31, 1883.

Application filed June 21, 1883. Term of patent 7 years.

To all whom it may concern:

Be it known that I, FREDERICK BEND, of Brooklyn, in the county of Kings and State of New York, have invented a new Design for Carpets, of which the following is a full, clear, and exact description.

This design relates to the appearance of woven carpet, produced by the combination of longitudinal stripes in colors with a twilled diamond pattern.

In the accompanying photograph of said carpet, the twilled figure runs diagonally in both directions, as shown at *a a*, and divides the surface up into small diamond patterns, and the warps are of different colors in stripes, as at *c d e f*, which stripes are repeated width-wise of the carpet. The peculiar artistic ef-

fect produced by the diamond pattern and the longitudinal stripes is pleasing to the eye in carpets of this class, and forms a new and ornamental design that is not dependent upon any particular colors of the stripes, as these may be varied.

I claim as my invention—

The ornamental design for a carpet, consisting in the longitudinal stripes and the diagonal diamond pattern, substantially as represented.

Signed by me this 15th day of June, A. D. 1883.

FREDERICK BEND.
